WELL DRILLING

George Dawson Priestman, Tulsa, Okla., and
Gerald Priestman, Elizabeth, N. J.

Application February 2, 1948, Serial No. 5,776

8 Claims. (Cl. 255—4)

1

The present invention relates to well drilling equipment useful for wells generally but primarily oil wells and in particular to equipment and method for continuously or semi-continuously feeding substantially rigid metal pipe of any length into a well either as a drilling string or casing or both.

The equipment herein is compact so that it may be mounted portably and allows replacement of the heavy cumbrous drilling equipment in common use such as a derrick without sacrifice of the normal utility thereof. Thus the present equipment lends itself to additional well drilling operations such as ordinary prospecting, and small hole drilling while being of equal utility for ordinary well drilling.

In its broadest concept, long lengths of metal pipe brought up to the well either in a coil or in separate lengths which may be welded together in a continuous string while lying flat on the ground in the neighborhood of the well bore, are first sent through a pipe bending machine to bring the straight length into a proper arc for feeding into the well and are then straightened in a pipe straightening machine which also acts as mechanism for applying or relieving pressure on the bit as desired at the top of the well for straightening and feeding the pipe under desired pressure as it passes down into the well, or the pipe, if already in a proper arc as unwound from a coil, may be passed directly to the pipe straightening machine and thence into the well without being first bent.

Thus, proceeding according to the present invention, long lengths of pipe are assembled on the ground through welding, made part of the drilling mud circuit and continuously fed into the well as drilling operations proceed with circulation of mud therethrough by continuously passing the pipe into the well, straightening the metal in a pipe straightener at the top of the well, or the pipe, if brought up in a continuous coil, is similarly made part of the well drilling mud circuit and fed into the well through the pipe straightener. In either or both instances the pipe, unreeled from the coil or brought up from the ground to the mouth of the well may be first passed through a pipe bending machine and thence through the pipe straightener after a proper arc is formed, if necessary. In this invention the drill pipe and bit driving mechanism or motor are non-rotating, and only the bit may be rotating or reciprocating in contrast to conventional drilling procedures in which the power

2

mechanisms at the surface rotate the drill pipe which in turn rotates the bit.

Reference is made to the accompanying drawing showing somewhat diagrammatically the drill rig assembly of the present invention.

Fig. 1 shows the pipe mounted as a coil on a reel;

Fig. 2 shows handling of pipe such as by welding into long lengths up on the ground;

Fig. 3 is a section through the reel showing the coils of pipe as mounted on the reel core; and

Fig. 4 is a modified detailed view of an end of the pipe and casing and drilling motor showing the use of concentric piping, comprising the casing and drilling string.

As will be noted, the several units are shown mounted on base elements 10 and 10' which may be pontoons, or which may be portably lifted onto a pontoon or portable truck, or the same units themselves may be provided with removable or securely anchored wheels so as to make them readily portable. The left hand pontoon of Fig. 1, 10', is mounted over a well 11 into which substantially rigid metal pipe string 12 is to be fed. At the lower end of the string is conventionally fixed a fluid pressure or other type of motor 13 to which is conventionally attached the drill bit 14. The bent pipe 12 is fed into the pipe straightener 15 rigidly mounted on the pontoon 10'.

The pipe straightener 15 comprises several roller elements 16 driven by a motor 17. As is conventional in pipe straighteners such rollers define at their adjacent peripheries a passageway for a straight pipe such that any pipe passed therethrough is rolled or ironed by rotation of rollers 16 into straight lengths. While this type of straightener is described as an example, other types of pipe straighteners known in the art, such as those employing heat for straightening the pipe, may be used as desired. From the rollers 16 the straightened pipe 12 passes down into the well rigidly suspending and advancing the drill bit and driving mechanism therefor, for supplying lubricant to the bit, supplying fluid pressure or power for operating the drilling motor and for generally controlling hydrostatic pressure in supplying mud or liquid for enhancing the pressure on the drilling bit.

The pipe 12 as shown in Fig. 1 is coiled on a reel 18, supported on standards 19 rigidly mounted on the base or pontoon 10. The reel 18 is journaled at 20 in the top of the standards 19 for rotation. The reel is constructed of outer

flanges 21 mounted on and separated by a core 22 as shown in Fig. 3. A driving motor 24, mounted on the base 10, is connected to the reel through any conventional driving gear mechanism such as gears or pulleys 25 and 26 for rotation and unwinding of the pipe coil on said reel at any desired rate.

Optionally mounted on the base 10 through supporting standards 27 is a pipe bender 28 through which pipe 12, as unwound from reel 18, may be caused to pass for bending into a desired arc for feeding from coil form to the pipe straightening unit 15. The pipe benders 28 comprise a series of roller elements 29 adjustable in relative position to each other to define an arc such that pipe 12 passing through the space defined at the adjacent peripheries of cooperative rollers 29 is bent gradually by each roller 29, 29a, 29b, etc., passing out of the device bent to the desired arc of curvature.

The core element 22 of the reel 18 is bored at 30 or formed as hollow pipe construction comprising the axis thereof from both or either end and is radially joined by a duct 31 to which the end of the coiled pipe 12 is fastened or coupled in a fluid type manner as with a pipe union, welded or otherwise. As shown, a pipe 32, carrying drilling fluid recycled from the well or from other source or carrying motor energizing fluid of the character of gas or liquid, or wire if an electric driving motor is used, is coupled to the duct 30 in a fluid tight manner at 33 by means of a stuffing gland or other known construction allowing the fluid circuit to be completed through the rotatable core 22 and thence through the pipe 12 connected thereto.

Power fluid or drilling mud is supplied to the pipe 32 through pump 34. Fluid supplied to the pump 34 at the suction end thereof may enter from outside the system through pipe 35 or may be recycled drilling fluid coming from the well through pipe 36. Fluid passing up from the well 11 may be first sent to an intermediate settling basin 37 and thence through a filter 38 before being recycled to the pump 34 by way of pipe 36.

In operation of this device the coiled pipe on reel 18 carries power fluid and/or lubricant sent through it through the entire length by way of pump 34, pipe 32, stuffing gland 33, core duct 30, and connecting pipe 31. The fluid passes into the well, driving the drilling motor 13 which rotates, reciprocates or oscillates the drill bit 14 lubricating the same and carrying away the cuttings while applying desired hydrostatic pressure at the bottom of the well. The drilling mud leaving the well together with the cuttings are first settled in basin 37 and then passed through filter 38 and is finally recycled to the pump 34. The drilling fluid may be analyzed for evidence of oil and rock types at any suitable point such as at the basin 37.

At the beginning of operations, drilling fluid or power medium for the drilling motor may be supplied through duct 35 and the introduction of fluid may be entirely through 35, as desired throughout drilling operations. It will be understood that any known power medium, gas or liquid, may be used, or for an electric motor only wires will be needed in which case the fluid acts only as a lubricant. Simultaneously, pipe is fed by uncoiling the pipe 12 from the reel 18 as rotated at desired rate by motor 24. If desired, the pipe 12 is sent through the pipe bender unit 28 as driven by motor 39 in synchronization with the rate of movement of the pipe therethrough.

The bent pipe is then fed through the pipe straightening unit 15 from whence it passes down into the well as straight substantially rigid metal pipe. The controlled rate of feed through the bending and straightening units and the uncoiling from the reel acts to assist in applying and relieving pressure on the bit, but these units may be further constructed with conventional braking elements (not shown) as desired to facilitate such control.

When the casing is to be withdrawn the operation is reversed and the metal pipe passing in reverse direction through the pipe bender unit 28 may be fed back onto the reel 18 in coil form. After one length of pipe has been used up the end of the pipe 12 may be uncoupled from pipe 31 and a new reel of pipe substituted for reel 18 and the end thereof joined to pipe 12 as by welding or otherwise.

In the modification shown in Fig. 2 pipe 12 is constructed of a single straight long pipe length assembled as such generally horizontally on the ground neighboring the well as by welding short lengths of suitable portable pipe lengths. One end of the straight pipe length is then coupled at 40 to the pressure side of the pump 34 from whence it is fed into a pipe bending unit 28 and thence through pipe straightener 15 passing down into the well. The power and mud circuit is otherwise the same as explained in Fig. 1 above. In this instance, as the pipe is fed into the well, the pump mounted on the pontoon 10 is moved closer to the well as the pipe length is used up. After using up an assembled pipe length a new long ground-assembled pipe length is welded to the end of the pipe 12 and coupled to the pump 34 at 40 the pump being moved to the proper position therefor and the operation continued.

While this invention is admirably adapted to small hole drilling, because the equipment is readily portable, any diameter size pipe may be used. In the case of large size pipe, it is usually preferable, rather than coiling the same, to weld, screw or otherwise join lengths of pipe on the ground and thence by means of a bender unit 28 followed by straightener unit 15 the pipe may be caused to enter the ground at any desired angle, normally vertically.

It will be apparent that, since various sizes of pipe may be used, double pipe may be fed into the ground in concentric relationship. The larger pipe may desirably act as casing and the inner pipe as a drill string, such as shown in detailed Fig. 4. As shown in this detail, the casing may be perforated, with suitably spaced holes, to allow passage of lubricating fluid between the casing and rock formation. In such application the pipe lengths are preferably assembled on the ground and both fed substantially concentrically through the pipe benders and pipe straightener, as described. It is possible to feed smaller sizes of concentric pipe in pre-assembled coil form also. Various pipe sizes are contemplated, ranging from 1" to 3" for drilling string and larger for casing.

The motor 13 may be of any known type, such as hydraulic turbine or reciprocating or oscillating type operated by the drilling mud or other power fluid and electric motors may also be used. It is substantially rigidly suspended and supported against rotation by the substantially rigid pipe 12 but may be further braced against the rotary torque by conventional means as known in the art.

As thus shown, drilling apparatus is taught, adapted to be portable and highly useful for exploratory purposes, using a single straight or coiled pipe length, or any number of pipe lengths welded together for conventional well drilling.

By ordinary metal pipe as the term is used herein will be understood the conventional steel pipe used in oil well drilling which, while it has a certain inherent strength, flexibility and rigidity as to require application of great force to bend and straighten the same as proposed herein, is critically distinguished from such pipe as rubber hose which may be relatively characterized as flabby and flimsy and neither has comparable utility for well drilling with the metal pipe nor would such rubber pipe require the use of bending and straightening devices as proposed herein.

Various modifications of the coil construction, the reel, the pipe bender and straightener, the pump, motor and means for purifying the drilling fluid will occur to those skilled in the art. It will also be apparent that any devices known and used in the drilling of wells which are lowered into the hole on conventional pipe or cable for obtaining cores, determining structures or bit locations may be applied to the non-rotating pipe as described herein. It is intended that the description be regarded as exemplary and not limiting and the invention be interpreted as broadly as defined in the claims.

We claim:

1. A well drilling unit comprising a motor, a well drilling bit connected to the motor for actuation thereby, means for raising and lowering said motor and bit in a well bore comprising a string of drill pipe, said pipe being characterized by being a single uninterrupted length of substantially rigid metal well drilling pipe capable of being bent beyond its elastic limit, means for feeding said drill pipe from a position wherein the pipe is normally disposed on the surface of the ground neighboring said well to the substantially vertical position of the pipe within the well wherein the drilling requires application of curvature to said pipe beyond the normal elastic limit thereof, said feeding means comprising a pipe curving means.

2. A well drilling rig for feeding a long continuous integral string of substantially rigid metal drill pipe requiring bending beyond the elastic limit of said pipe to form an arc to feed the pipe from a position on the ground adjacent the well to the substantially vertical position of the pipe wherein the pipe enters the well in the

drilling thereof, having a drilling motor mounted on the inner end of said pipe within the well and a drilling bit mounted on said motor for actuation thereby, comprising a pipe bender mounted adjacent said well through which the pipe is continuously fed, said pipe bender adapted to bend said pipe beyond the elastic limit thereof to form an arc suitable for entering said well from the position of the pipe on the ground, and a pipe straightener mounted above the well bore through which the bent pipe passes for continuously straightening said bent pipe and feeding the same into the well in the drilling thereof.

3. The drilling rig as defined in claim 1 wherein in the outer end of the pipe is bent beyond the elastic limit in a coil about a reel and then passed to said pipe feeding means.

4. The drilling rig as defined in claim 1 having means for continuously passing drilling fluid into the outer end of said pipe.

5. The drilling rig as defined in claim 1 wherein the pipe comprises two pipes, a larger diameter pipe and a smaller diameter pipe disposed one within the other.

6. The drilling rig as defined in claim 2 wherein in the outer end of the pipe is bent beyond the elastic limit in a coil about a reel and then passed to said pipe feeding means.

7. The drilling rig as defined in claim 2 having means for continuously passing drilling fluid into the outer end of said pipe.

8. The drilling rig as defined in claim 2 wherein the pipe comprises two pipes, a larger diameter pipe and a smaller diameter pipe disposed one within the other.
